UNITED STATES PATENT OFFICE.

FRED ORANGE, OF OTTAWA, ONTARIO, CANADA.

STAIR RUG.

Application filed October 11, 1926 Serial No. 141,016.

This invention relates to improvements in stair rugs and the objects of the invention are to provide a detachable rug for stairs and the like that will be more sanitary, that can be 5 securely fastened thereon and that will be much less expensive to manufacture and fit, while at the same time adding to the appearance of the stairs or series of steps.

A further object is to provide a combination pad and stair rug adapted to automatically engage with and grip the edge of the steps of a stair.

Yet another object is to provide a rug or carpet with spring actuated reinforcing means imbedded therein whereby the rug or carpet is adapted to grip and fit snugly on the stair and is also prevented from turning up at the corners when used in ordinary flat position on a floor.

With the foregoing and other objects hereafter more fully referred to in view my invention comprises a rug provided with a suitable pad or lining having imbedded therein adjacent the edges flat strips of resilient material whereby the rug is reinforced to grip when bent over the edge of a step or in flat position to prevent the rug or carpet from turning up at the corners.

Referring now to the drawings in which like characters of reference indicate corresponding parts in each figure.

Figure 1 is a perspective view of a section of a stair fitted with my improved stair rug or carpet.

Figure 2 is a plan view of the under side of the rug.

Figure 3 is a sectional view through a step fitted with the rug.

In the drawings 10 designates a stairs or series of steps on each of which is designed to fit, with or without fastenings, my improved rug comprising an ordinary rug or section of carpet 11 made to size. On the back of the rug is a lining 12 of any suitable material secured thereto in any well known manner. Between the lining and the back of the rug, as illustrated in Figure 2, adjacent each end 13 and 14, are secured metallic strips 15 and 16 extending transversely of the rug and bent, as illustrated in Figure 3, to conform to the contour of the outer edge 17 of a

step 18 to grip it and hold the rug snugly in position on the body of the step as at 19.

For more securely gripping the step and also prolonging the wear of the rug I provide 55 a metallic edging strip 20 secured on the rug in any well known manner. The opposite edge of the rug to the folded or stair gripping edge, is preferably reinforced by a metallic strip 21, the base of the rug being folded 60 over the strip, as at 22, and having arranged therein a plurality of spaced orifices 23 designed to engage with securing pins or ornamental heads 24, as illustrated in Figure 1, to fixedly retain the carpet or rug on the stairs 65 or floor. These auxiliary fasteners may be dispensed with as the bent resilient members in the rug form in combination with the metal edging adequate means for retaining the rug on a step or the like.

From the foregoing it will be seen that I have invented a rug, a preferred example of this is herein described and illustrated, that while taking the place of the ordinary continuous stair carpet can be placed on the 75 market to accomplish the same results in a more sanitary manner at approximately 50% less cost with a corresponding reduction in the amount of material used. My improved rug, it will be seen, combines in one a stair 80 rug, a pad and means for securing it, thus eliminating the rods, fixed fasteners and stair pads.

For ordinary floor carpets the reinforcing strips 21 or resilient material will be secured 85 adjacent the edges of the rug in the corners on the back of the rug with or without lining, thereby retaining the corners flat without, as so often happens, it becoming spoiled by turning up and getting in the way of individuals or having to be tacked down which spoils the carpet.

As many changes could be made in the above construction and many apparently widely different embodiments of my invention within the scope of the claim, constructed without departing from the spirit or scope thereof, it is intended that all matter contained in the accompanying specification and drawings shall be interpreted as illustrative 100 and not in a limiting sense.

What I claim as my invention is:

A flexibly reinforced carpet for stairs, floors and the like, comprising in combination a rug section adapted to fit the steps of stairs and to extend over the edge thereof, flexible metallic strips secured on the under side of said section at each side and adapted to be bent to form a resilient gripping portion for the edge of the step and when unbent to re-

tain the edges and corners of the section flat, a metallic edging for the strip and an auxiliary reinforcing cross strip for the section.

In witness whereof I have hereunto set my hand.

FRED ORANGE
